UNITED STATES PATENT OFFICE.

WILLIAM A. AINSWORTH, OF GRAND RAPIDS, MICHIGAN, ASSIGNOR OF ONE-HALF TO
CARL N. MATHER, OF GRAND RAPIDS, MICHIGAN.

WINDING AND DYEING MACHINE.

1,274,972.

Specification of Letters Patent.

Patented Aug. 6, 1918.

Application filed July 16, 1917. Serial No. 180,805.

To all whom it may concern:

Be it known that I, WILLIAM A. AINSWORTH, a citizen of the United States of America, residing at Grand Rapids, in the county of Kent and State of Michigan, have invented certain new and useful Improvements in Winding and Dyeing Machines; and I do hereby declare the following to be a full, clear, and exact description of the invention, such as will enable others skilled in the art to which it appertains to make and use the same.

This invention relates to a machine or mechanism for winding yarns or similar materials such as are used in the manufacture of knitted fabrics, and consists in mechanism applied to said machine whereby the yarn, thread, or other like material may be dyed, stained, or colored, either in intermittent or continuous lengths as said material travels from one cone, bobbin, or skein, to another.

Yarn, thread, or similar fibrous material furnished to the manufacturer of knitted fabrics, is first applied to a winding machine by means of which it is wound on proper sizes and shapes of cones or bobbins for use in the various knitting machines which make the knitted fabric, and it is during this process of winding that my invention works to either intermittently or continuously dye, stain, or color the same.

For an understanding of the invention, reference may be had to the accompanying drawing showing the same in preferred form and in which:

Figure 1 is an end elevation of a winding machine equipped with my invention.

Fig. 2 is a perspective view looking toward a side and end of the machine.

Fig. 3 is an enlarged vertical section illustrating particularly the dyeing, staining, or coloring mechanism applied to the winding machine.

Figs. 4 and 5 show in end and side elevation one element of the dyeing, staining, or coloring mechanism, and

Fig. 6 is a perspective view, with parts broken away, of one end of the dye-containing tank or receptacle.

Like reference characters refer to like parts in the several views of the drawing.

The winding machine in construction comprises spaced apart end frames 1 which are connected by lower bars 2 and upper

bars 3 and 4, to make a rigid frame. At each side of the frame there is provided an outwardly extending shelf or platform 5, serving as a support for a plurality of cones, bobbins, or the like, shown at 6, on which 60 yarn, thread, or other fibrous material is carried, said yarn being in the form as it comes from the manufacturer of yarns to the manufacturer of knit fabrics. Vertical spindles 7 mounted for rotation about vertical axes form elements of the winding machine, each carrying a cone, bobbin, or the like, as indicated at 6^a, on which the yarn, thread, or the like, is wound by the machine prior to its use in a knitting machine. The 70 yarn or thread passes over a rest 8 projecting from a nut 9, threaded on to a vertical screw-threaded rod 10, one of such rods 10 being provided for each spindle 7. The thread likewise passes under a rod 8^a, carried in any suitable manner above the bar 4. In practice the screw-threaded rods 10 are power driven and at proper points reverse in their movements so as to carry the thread up and down and guide it properly 80 with respect to the cone or bobbin 6^a.

As a part of the winding machine mechanism, there is included a wheel 11, mounted for rotation and driven from any suitable source of power. It in turn, through a belt, 85 drives a second wheel 13, which through suitable mechanism is adapted to drive the plurality of spindles 7 and screw-threaded rods 10 heretofore described. Inasmuch as the specific mechanism for driving the spindles 7 and rods 10 forms no part of the present invention, it is not shown nor described in detail.

At each side of the machine above the bar 4 and mounted on suitable brackets carried 95 thereby, is a tank 14, in which a quantity of dye, stain, or coloring matter 15 in liquid form is carried. A plurality of supports 16 are fixed to the tank and extend a short distance thereabove, each at its upper end 100 carrying a suitable guide 17, through which the yarn or thread may pass from the cone or bobbin 6 as it is unwound by the machine. There are, of course, as many supports 16 and guides 17, as there are cones 105 or bobbins 6 to be unwound, and the number may be varied or changed at will. Likewise a plurality of wicks 18 are carried by the tank 14 and extend into the coloring fluid, the upper end of each wick extending 110

a short distance above the tank as indicated at 19, the thread or yarn normally passing immediately above said upper end of its associated wick.

5 A bracket 20 is secured adjacent each end of the tank 14, and on the side opposite the support 16. A shaft 21 is rotatably supported by and between brackets 20 and in the length thereof, there are fixed a plurality of collars 22, from each of which extend fingers 23, paralleling the shaft 21. In the drawing, I have shown two of these fingers 23 although the number may be increased or diminished as desired. On the shaft to which wheel 13 is fixed, two pulleys 24 are secured around which endless belts 25 pass, leading in opposite directions to and around pulleys 26, one of which is fastened at an end of each shaft 21, it being apparent that when the machine is operated, shafts 21 are continually rotated; the collars 22 with attached fingers 23 turning with the shafts.

In operation, the rotation of spindles 7 causes a winding of the thread, yarn, or like material on the cones or bobbins 6^a, drawing and unwinding the same from the cones or bobbins 6 and drawing it past the upper end 19 of its associated wick 18. The 20 thread or yarn passes normally underneath the fingers 23 of one of the collars 22. It will be apparent that the rotation of shaft 21 with the consequent movement of the fingers 23, causes said fingers to intermittently 25 engage against the thread or yarn, depressing it into contact with the end 19 of a wick 18 whereby dye or similar coloring matter is applied to the thread until such time as the pressure of the finger 23 is removed, whereupon the yarn or thread is 30 released and moves over and above the wick until again depressed by the succeeding finger 23. This action causes the yarn or thread to be dyed, stained or colored in 35 intermittent lengths with other lengths of uncolored yarn or thread between that which has been dyed or colored. This is a desirable feature in that the yarn thus dyed or stained when knit into a fabric, produces a 40 fabric in which a variegated color effect and appearance is made. Of course, it is possible to stain or color the yarn continuously by merely turning the shaft 21 to a position such that one of the fingers 23 holds the 45 yarn or thread in depressed position and then drawing the yarn under said finger, shaft 21 remaining at rest.

Preferably a shaft 27 extends lengthwise of each tank or receptacle 14 on which a 50 plurality of paddles or stirrers 28 are fixed. At one end of each shaft a pulley 29 is secured. It is desirable to rotate the shafts continuously at low speed in order to stir the liquid coloring matter that it shall 55 always be of uniform color and not have

any sediment or coloring matter settle to the bottom of the receptacle. This may be accomplished in a variety of ways.

As one way I have shown a gear 30 equipped with a double driving pulley 32, 70 belts 33 leading therefrom to and around the pulleys 29 on the ends of shafts 27, it being clear that such construction attains a continuous and relatively slow turning movement of shafts 27 whenever the gear 75 is in motion. The shaft on which gear 30 is mounted is driven from any suitable source of power and the gear meshes with a pinion 31 attached either to wheel 11 or the shaft on which the wheel is fixed for 80 driving said wheel.

I have described the operation of the mechanism with respect to one cone or bobbin of the thread or yarn, but the same applies to all, the action being identical in each 85 case. A machine of the character described may be used to intermittently stain, dye, or color yarns and like fibrous materials, and a great quantity can be acted upon with little or no expense. The operation as at present carried on for intermittently coloring, staining or dyeing yarns or the like, is relatively costly involving considerable handling, waste and shrinkage of the material 90 which is avoided with my invention. 95

I claim:—

1. In a winding and dyeing machine, means to transfer thread, yarn, or like material from one holder therefor to another, and means to intermittently apply coloring 100 matter to the length thereof as it is transferred, substantially as described.

2. In a winding and dyeing machine, means to transfer thread, yarn, or the like from one holder therefor to another, a receptacle containing coloring matter adjacent which said material passes, and means for periodically bringing said material into contact with the coloring matter, whereby the material has lengths alternately colored 110 and uncolored, substantially as described.

3. In a winding and dyeing machine, means to transfer thread, yarn, or like material from one holder therefor to another, a receptacle containing liquid coloring matter 115 over which said material passes, a wick extending into the coloring matter and having its upper end located above the receptacle and normally immediately below said passing material, and means to periodically depress said material into contact with the wick as it passes thereover. 120

4. In a machine containing the elements in combination defined in claim 3, combined with means for stirring the coloring 125 matter while the transfer means is in operation.

5. A mechanism containing the elements in combination claimed in claim 2 in which the means for periodically bringing the ma- 130

terial into contact with the coloring matter consists of a rotatably mounted collar, a finger projecting from the collar adjacent which the material passes, and means to 5 turn the collar whereby said finger periodically engages against the material and brings it into contact with said coloring matter, substantially as described.

6. A machine containing the elements in 10 combination defined in claim 3, combined with a shaft extending through the receptacle containing the coloring matter, stirrers fixed to the shaft, and means for turning the shaft.

15 7. An attachment adapted for application to winding machines for yarn or like material including a receptacle for containing liquid coloring matter, over which the yarn is adapted to pass, said receptacle having 20 cylindrical form and adapted to lie lengthwise of the machine, a plurality of wicks in the receptacle extending a short distance thereabove, a shaft paralleling the receptacle, a plurality of collars, one for each wick 25 secured on the shaft, and fingers under which the yarn is adapted to pass projecting laterally from each collar.

8. In a winding and dyeing machine, 30 means to transfer thread, yarn or like material from one holder therefor to another, a member impregnated with coloring material closely adjacent which the thread, yarn or like material normally passes, and movable means located between one of the hold-

ers and said member and operable to intermittently press against the thread, yarn or like material to periodically bring the same into contact engagement with said member, whereby said material is wiped across the member and receives coloring matter therefrom, intermittently applied in the length of the material, substantially as described. 35

9. In a winding and dyeing machine, 40 means to transfer thread, yarn or like material from one holder therefor to another, a member impregnated with coloring matter adjacent which the thread, yarn or like material normally passes, and means for intermittently pressing said material against said member whereby said material is intermittently wiped against the member as it passes the same and receives coloring matter therefrom intermittently in the length of 45 said material, substantially as described. 50

10. In a winding and dyeing machine, 55 means to transfer thread, yarn or like material from one holder therefor to another, a member impregnated with coloring matter between the holders and adjacent which the thread, yarn or like material normally 60 passes, and means for intermittently wiping said material against said member as the material passes the same whereby intermittent lengths of the material are colored, substantially as described. 65

In testimony whereof I affix my signature.

WILLIAM A. AINSWORTH.
